UNITED STATES PATENT OFFICE.

SAMUEL HELLER, OF NEW YORK, N. Y., ASSIGNOR TO L. HELLER & SON, INC., OF NEW YORK, N. Y., A CORPORATION OF NEW YORK.

DESIGN FOR A JEWELRY BOX.

Application filed March 5, 1924. Serial No. 8,838. Term of patent 3½ years.

To all whom it may concern:

Be it known that I, SAMUEL HELLER, a citizen of the United States, residing at New York, in the county and State of New York, have invented a new, original, and ornamental Design for a Jewelry Box, of which the following is a specification, reference being had to the accompanying drawing, forming part thereof.

The figure is a perspective view of a jewelry box when closed showing my new design.

I claim:

The ornamental design for a jewelry box as shown.

SAMUEL HELLER.
